UNITED STATES PATENT OFFICE.

PHILLIP DANIEL SERRURIER, OF SAVANNA, ILLINOIS.

GUARD-RAIL.

1,024,952.

Specification of Letters Patent.

Patented Apr. 30, 1912.

Application filed June 21, 1911. Serial No. 634,417.

To all whom it may concern:

Be it known that I, PHILLIP D. SERRURIER, a citizen of the United States, and a resident of Savanna, in the county of Carroll and State of Illinois, have invented a new and Improved Guard-Rail, of which the following is a full, clear, and exact description.

This invention relates to a new and improved guard rail for a railroad or car track.

An object of this invention is to provide a guard rail which will be simple in construction, inexpensive to manufacture, strong, durable, readily adjustable, positively safe in its action, and self-bracing.

A further object of this invention is to provide a guard rail which may extend under the rail proper and be secured to the opposite side thereof, so that it cannot be readily turned over or be pulled out, and is so formed that it will not be liable to catch the foot of a track-walker.

These and further objects, together with the construction and combination of parts, will be more fully described hereinafter and particularly set forth in the claims.

Reference is to be had to the accompanying drawings forming a part of this specification, in which similar characters of reference indicate corresponding parts in all the views, and in which—

Figure 1 is a fragmentary top plan view; Fig. 2 is a side view in elevation, with the guard rail in position on the ties, and with the track rail omitted for the sake of clearness; Fig. 3 is a vertical transverse section; and Fig. 4 is a perspective view of the guard rail detached.

Referring more particularly to the separate parts of this invention as embodied in the form shown in the drawings, 1 indicates a track rail, which is supported in any usual manner on ties 2. Arranged alongside of the track rail 1, there is provided a guard rail 3, which has a plurality of openings 4 along one side thereof, whereby it may be attached by means of spikes 5 to the ties 2. The guard rail may embody a main body portion 6, from the lower side of which extend a plurality of arms 7,

8 and 9, which are adapted to pass under the track rail 1 a sufficient distance, so that brackets 10 provided on the free ends thereof and projecting upwardly therefrom may overhang at either side the ties 2 and be secured thereto by means of spikes 11 passing through apertures 12 in the overhanging portion of these brackets. It will be noted that these brackets 10 are raised above the surfaces of the arms 9 sufficiently to form a ridge, which may abut against the flange of the track rail 1 and prevent the accidental movement of the guard rail relative to the track rail. The bottom sides of the arms 7 and 9 may be provided with downwardly-extending ribs 13, which are adapted to engage in the roadbed and prevent longitudinal slipping or shifting of the guard rail. It will be noted that the corners on the ends of the guard rail which face the track rail are cut away at 14 and 15, so that the wheels of the car can readily pass between the track rail and the guard rail, on entering the stretch where the guard rail is used in connection with the track rail. At this point and any other suitable points desired, the guard rail may be provided with foot guards 16, which, it will be noted by reference to Fig. 3, come up in close juxtaposition to the head of the track rail 1 and enter the channel formed between the head and the flange of the track rail a slight distance, so as to prevent the foot of a track-walker or other person from being caught between the track rail and the guard rail.

It will be noted that the guards 16 may be formed co-extensive with the arms 7 to 9 and may provide enlargements 17 thereon, which are cut away at 18 so as to form overhangs which overhang the flange of the track rail 1, and thus aid in securing the guard rail in position alongside of the track rail.

The utility of the device will be readily understood when taken in connection with the above description. In placing the guard rail in position, the roadbed is dug out sufficiently alongside of the track, and the arms 7, 8 and 9 slipped beneath the rail a sufficient distance so that they can be shoved up

alongside of the ties 2, to a position in which the ends of the brackets 10 overhang the ties 2, when these brackets and the guard rail forming a part thereof can be secured to the ties by spikes 11 being driven through the apertures 12 and the ties 2. The guard rail can be secured on the opposite side by the spikes 5, which are driven through the apertures 4 into the ties which come beneath them. The distance of the brackets 10 on the guard rail from the body portion is so regulated that the longitudinal working face, indicated at 20, of the guard rail, will be spaced apart from the track rail 1 a sufficient distance to permit the flange of the wheel on the car to pass between them.

It will be seen that by virtue of the contact of the bracket 10 with the track rail 1 on one side and the overhanging of the enlargements 17 on the other side, the guard rail will be secured fixedly, not only to the ties 2, but also to the track rail 1. The flat foot guards, by virtue of their location and extension, will prevent the foot of a track-walker from being jammed between the track rail and the guard rail.

While I have shown one embodiment of my invention, I do not wish to be limited to the specific details thereof, but desire to be protected in various changes, alterations and modifications which may come within the scope of the appended claims.

Having thus described my invention, I claim as new and desire to secure by Letters Patent:—

1. A guard rail adapted to coöperate with a track rail, comprising a body portion having the corners of the side thereof facing said track rail cut away to permit the entrance of the wheels of a car between said track rail and said guard rail, and foot guards located beneath these cut-away portions and adapted to prevent the entrapping of a foot between said guard rail and said track rail, said foot guards extending into the channel formed between the head and flange of said track rail, and also coming in close juxtaposition to said head.

2. A guard rail adapted to extend alongside of a track rail to prevent the wheels of a car from leaving said track rail, said guard rail comprising a body portion, and a plurality of arms extending from one side of said body portion and adapted to extend under said track rail, said arms having brackets thereon projecting from either side thereof and extending upwardly so as to engage the flange of said track rail on the opposite side of said track rail from which said body portion is located, said body portion having enlargements connected thereto and co-extensive with said arms, said enlargements overhanging the opposite flange

of said track rail from which said brackets engage, whereby said guard rail is secured to said track rail.

3. A guard rail adapted to extend alongside of a track rail to prevent the wheels of a car from leaving said track rail, said guard rail comprising a body portion, and a plurality of arms extending from one side of said body portion and adapted to extend under said track rail, said arms having brackets thereon projecting from either side thereof and extending upwardly so as to engage the flange of said track rail on the opposite side of said track rail from which said body portion is located, said body portion having enlargements connected thereto and co-extensive with said arms, said enlargements overhanging the opposite flange of said track rail from which said brackets engage, whereby said guard rail is secured to said track rail, said body portion and said brackets having apertures therein, whereby said guard rail may be spiked to the ties supporting said track rail.

4. A guard rail adapted to extend alongside of a track rail to prevent the wheels of a car from leaving said track rail, said guard rail comprising a body portion, and a plurality of arms extending from one side of said body portion and adapted to extend under said track rail, said arms having brackets thereon projecting from either side thereof and extending upwardly so as to engage the flange of said track rail on the opposite side of said track rail from which said body portion is located, said body portion having enlargements connected thereto and co-extensive with said arms, said enlargements overhanging the opposite flange of said track rail from which said brackets engage, whereby said guard rail is secured to said track rail, said body portion and said brackets having apertures therein, whereby said guard rail may be spiked to the ties supporting said track rail.

5. A guard rail adapted to coöperate with a track rail, comprising a body portion having the corners of the side thereof facing said track rail cut away to permit the entrance of the wheels of a car between said track rail and said guard rail, foot guards located beneath these cut-away portions and adapted to prevent the entrapping of a foot between said guard rail and said track rail, said foot guards extending into the channel formed between the head and flange of said track rail, and also coming in close juxtaposition to said head, arms projecting from one side of said body portion, and brackets secured to the free ends of said arms and projecting from each side thereof, said brackets extending above the upper face of said arms so as to form a projection adapt-

ed to engage the flange on said track rail, said brackets having apertures therein, whereby they may be spiked to the ties supporting said track rail, said arms having 5 ribs extending downwardly from their under sides, whereby the guard rail is prevented from longitudinal movement relative to said track rail.

In testimony whereof I have signed my name to this specification in the presence of 10 two subscribing witnesses.

PHILLIP DANIEL SERRURIER.
